UNITED STATES PATENT OFFICE.

CHARLES B. BUERGER, OF PITTSBURGH, PENNSYLVANIA, ASSIGNOR TO GULF REFINING COMPANY, OF PITTSBURGH, PENNSYLVANIA, A CORPORATION OF TEXAS.

PROCESS OF CONVERTING HIGHER-BOILING PETROLEUM HYDROCARBONS INTO LOWER-BOILING PETROLEUM HYDROCARBONS.

Application filed July 22, 1925. Serial No. 45,330.

This invention relates to processes of converting higher boiling petroleum hydrocarbons into lower boiling petroleum hydrocarbons and it comprises distilling the 5 higher boiling hydrocarbons in the presence of aluminum chlorid to convert the higher boiling hydrocarbons into lower boiling hydrocarbons, passing the vapors produced together with any hydrochloric acid which 10 may be produced to condensing means, contacting the said vapors with sufficient water to condense the major portion of them and to dissolve the hydrochloric acid and delivering the water, hydrochloric acid solution 15 and condensed vapors below the surface of a column of water and allowing gravitational separation of the condensed hydrocarbons and water while withdrawing the condensed hydrocarbons and maintaining the level of 20 the column of water substantially constant by continuous withdrawal of a portion thereof; all as more fully hereinafter set forth and as claimed.

In the art of distilling and converting petroleum hydrocarbons with the aid of aluminum chlorid, several different methods have been proposed and used. In one such method reflux condensers are employed in the vapor line between the still and the 25 final water cooled condensers so that there is refluxed back to the still condensed aluminum chlorid or aluminum chlorid-hydrocarbon compounds together with higher boiling oils. This method of distillation has 30 many advantages, among them being the possibility of preventing clogging of the final water cooled condensers by aluminum chlorid carried over. But as the high boiling oil operated upon is sometimes not absolutely dry and may contain oxygen in other 35 forms, there will often be a formation of hydrochloric acid vapors which will go forward to the final condenser.

Under some conditions in distillation no 40 reflux is used between the still and the final water cooled condenser. This being particularly so when the distillation is conducted to obtain a certain character of distillate by using a relatively small proportion of aluminum chlorid, and in this case traces, and 45 sometimes appreciable amounts of aluminum chlorid, as well as hydrochloric acid vapors, (if the oil contains oxygen or any moisture), will go forward to the final condenser. The

aluminum chlorid used is usually made 55 from bauxite which contains small proportions of titanium oxid, silicon oxid, iron oxid, etc., so that it is not pure but contains greater or less proportions of titanium chlorid, silicon chlorid and iron chlorid. To 60 some extent these accompany the oily vapors produced when the aluminum chlorid is used for converting higher boiling hydrocarbons into lower boiling hydrocarbons.

It is the object of the present invention 65 to obviate dangers of corrosion arising from these causes. I have discovered that the coils of the final water cooled condenser can be completely protected against entrance of hydrochloric acid vapors or of any substantial amount of chlorids, regardless of the character of the aluminum chlorid distillation or of the particular grade of chlorid used, by condensing some or most of the oily vapors produced in aluminum chlorid distillation through the agency of water, and I advantageously do this in a tower; passing the oily vapors which contain small amounts of chlorids including hydrogen chlorid, to a tower and in the tower spraying these vapors with sufficient water to condense most of them and to dissolve chlorids and hydrochloric acid. The water used, the hydrochloric acid solution and the condensate from the vapors together with any 70 sludge formed from the chlorids, and any other solid product, are delivered below the level of a column of water maintained in the tower and the condensed oil is allowed to rise and is withdrawn while the column 75 level is maintained substantially constant by continuous withdrawal of water at a low point. The accumulated sludge is withdrawn from time to time.

In the accompanying drawings showing 80 one form of apparatus suitable for the performance of my process,

Fig. 1 is a view partly in section and partly in side elevation of a still, the condensing tower and cooling box;

Fig. 2 is a vertical section on line 2-2 of Fig. 1 looking in the direction of the arrows;

Fig. 3 is an enlarged horizontal section along line 3-3 of Fig. 1; and

Fig. 4 is a segmental side elevation of the lower portion of the tower looking in the direction of the arrow marked 4,

105

In the drawings, 1 indicates an ordinary type of still provided with shaft 2 for the usual stirring apparatus and having a vapor outlet 3, all diagrammatically shown. The vapor outlet 3 of the still is connected to the tower at 4 to deliver vapors of lower boiling hydrocarbons resulting from the distillation of higher boiling hydrocarbons in the presence of aluminum chlorid in the still 1. The condensing tower comprises a shell 5 of steel or the like interiorly lined with acid proof bricks 6 of silica or the like and is closed at the top by cover 7 carrying an access manhole 8. At the bottom the tower is provided with manhole and cover 9. Supported on the grating 10 are a plurality of hollow tile 11 and immediately above these is provided a distributing box 12. Above the distributing box is the outlet 13 of the water pipe 14 arranged to deliver water into the distributing box whence it flows over and through the tile past the grating 10 into the lower portion of the tower against the rising oily vapors delivered from the still by means of the vapor line 3. The water is supplied through line 14 in such an amount as to condense and wash down the bulk of vapors of the oil. Below the vapor line inlet is the funnel 15 supported in the lining at 16 and having a leg depending below the normal level of the water in the tower. This funnel collects the condensed oil and water and delivers them below the level of the water in the tower so as not to unduly disturb the water. The oil and water separate, the oil overlying the water, and the oil is constantly delivered to cooling worms in the cooling box 17 by means of the pipe 18. In order that the pressure may be equalized between the outlet for the oil and the tower thereabove, equalizing pipe 19 is provided. Any vapors or non-condensable gases which escape past the water spray may enter this pipe at the top and are delivered to the cooling coil. Should there be slight pressure in the other direction these vapors or gases would flow upwardly through the equalizing pipe 19 and would be carried down by the water spray. The volume of water in the tower is kept substantially constant by withdrawal through the pipe 20 in communication with the lower portion of the tower through line 22. This pipe rises upwardly outside the tower to a point past the normal water level in the tower and, as shown, terminates outside the tower at 23 and at a point approximately level with the vapor inlet and with open top to prevent vacuum formation. At a point slightly below the oil outlet 18 a branch pipe 24 attached to the withdrawal pipe 20 carries water from such pipe to the conduit 25 leading to the sewer. Preferably between the conduit 25 and the pipe 24 is the funnel-like enlargement 26. The end of the pipe 24 terminates just above or in it in order that the character of waste may be observed. The line 22 carries a valve 21 so that aluminum oxid, titanium oxid, iron oxid and other solid matters formed from the 70 matters carried over may be continuously or intermittently withdrawn by operation of this valve. In the process of distilling with aluminum chlorid and condensing with water as described, there is formation of certain solid substances or sludges. Some of the aluminum chlorid is carried down by the water and oxids, and hydrates are formed and if there is any titanium chlorid in the aluminum chlorid, this will also be scrubbed 75 out in oxidized form so that unless some means for withdrawing these sludges is provided, the line 20 is likely to become clogged and the condenser fail to work. Ferric chlorid remains in solution to some extent. 80 Silicon chlorid gives solid silica. 85

If for any reason, the flow of water should be obstructed or the water should not be carried away at a sufficiently rapid rate to compensate for the introduction of the water 90 or, if for any reason, water should accumulate in the upper or vapor space in the tower, means are provided for immediately causing an overflow. The safety overflow arrangement comprises the pipe 27 in communication with the tower at a relatively low point as at 28 below the level of the water, and in communication with the tower at a relatively high point as at 29 above the vapor inlet. In communication with this pipe 27 at 30 is the 100 water leg 31 terminating at a level slightly below the connection 29. This safety overflow arrangement prevents flow of water to the still should the water over flow 20 or the line 18 become clogged. The vapor line 3 105 extends to a higher level than pipe 29 as at A.

It is believed the operation of the apparatus is obvious from the foregoing.

The higher boiling hydrocarbons are distilled in the presence of aluminum chlorid in still 1 while the stirring apparatus is operated and oily vapors carrying traces, or a little more than traces, of titanium, iron and aluminum chlorid, etc. and of hydrochloric acid vapors are carried by means of vapor line 3 to the tower 5. Water is introduced to the tower through line 14 and the ascending vapors are scrubbed by means of the descending water. Oil and water 110 separate in the tower and the outflow of water through line 20 is so regulated that the oil level is maintained at the oil outlet 18. Scrubbed, washed and separated oil is constantly delivered to the cooling worm 115 (not shown) in the cooling box 17 while the water is constantly removed from a lower portion of the column by means of pipe 20 and pipe 24 connected with line 20 at a high point. This connection insures that the 120 125 130

water shall not all be drained from the tank. In other words, the water cannot be removed by pipes 20 and 24 below the level of the point of connection of these two pipes. The valve 21 is opened from time to time in order that sludges may be removed. This is best done at a time when the distillation process in still 1 has been completed and the still is being prepared for another charge. Uncondensed gases and vapors after passing the tile go to the cooling worm through the equalizer pipe 19. Vapors coming from the still are sealed against direct communication with the pipe 18 by means of the funnel 15.

Ordinarily the temperature of the oil and water at the point of separation is from 150° to 200° F. All the hydrochloric acid and any iron, titanium, silicon and aluminum chlorides or oxides are removed, as well as other impurities and pure lower boiling hydrocarbons are collected in the cooling worm which is thus protected against corrosion and fouling.

What I claim is:—

1. In the process of distilling higher boiling hydrocarbons with aluminum chlorid to produce lower boiling hydrocarbons, the step which consists in condensing the produced oily vapors by means of water contacted with them and removing any chlorids, hydrochloric acid and other foreign matters from the vapors by means of such water.

2. The process of converting higher boiling petroleum hydrocarbons into lower boiling petroleum hydrocarbons which comprises distilling the higher boiling hydrocarbons in the presence of aluminum chlorid and passing the vapors, together with any hydrochloric acid produced, to a scrubbing device holding a column of water, contacting the vapors in the scrubbing device with sufficient water added above the column to condense hydrocarbon vapors and to dissolve any hydrochloric acid while cleaning such vapors of chlorids and other impurities, delivering the water, the hydrochloric acid solution and condensed vapors, as well as separated impurities, below the level of the column of water and allowing gravitational separation of the condensed hydrocarbons and the water, withdrawing the condensed hydrocarbons, maintaining the column of water substantially constant by continuous withdrawal of a portion thereof, and removing from the column of water all solid collected

sludges, such as products formed from the chlorids in the vapors.

3. The process of condensing vapors of hydrocarbons produced by an aluminum chlorid distillation, which comprises scrubbing and condensing such vapors with water, delivering all condensed matters to a column of water, allowing gravitational separation of the oil and water and removing the oil from the top of the column, while constantly withdrawing water from the bottom of the column and removing at a low point in the column of water from time to time accumulated sludge occasioned by solids coming from the vapors.

4. The process of purifying and condensing vapors of petroleum hydrocarbons produced by distillation with aluminum chlorid made from bauxite, which comprises scrubbing and condensing such vapors with water to remove chlorids accompanying them, delivering the products of such scrubbing, including condensed oil, to a column of water, removing the condensed oil from the top thereof, and drawing off from a low point of said column the solid products formed by the chlorids removed from the vapors by means of the water.

5. The process of converting higher boiling hydrocarbons into lower boiling hydrocarbons, which comprises distilling the higher boiling hydrocarbons in the presence of aluminum chlorid, passing the vapors, together with any hydrochloric acid produced, to a tower containing water, contacting the vapors and the hydrochloric acid with sufficient added water to condense the vapors and dissolve the hydrochloric acid, delivering the water, hydrochloric acid solution and condensed vapors below the column of water and allowing gravitational separation of the condensed hydrocarbons and water, withdrawing the condensed hydrocarbons, and maintaining the level of the column of water substantially constant by continuous withdrawal of a proportion thereof.

6. In the production of oily distillate from high boiling hydrocarbons by aluminum chlorid, the process of eliminating chlorids and hydrochloric acid from such distillates which comprises scrubbing the distillation vapors immediately after their production with water prior to condensation.

In testimony whereof, I have hereunto affixed my signature.

CHARLES B. BUERGER.
